UNITED STATES PATENT OFFICE.

ROBERT C. EDDY, OF MILWAUKEE, WISCONSIN.

DESIGN FOR A RUBBER BALL.

54,903.

Specification for Design.

Patented Apr. 20, 1920.

Application filed April 23, 1917. Serial No. 164,063. Term of patent 14 years.

To all whom it may concern:

Be it known that I, ROBERT C. EDDY, a citizen of the United States, residing at Milwaukee, in the county of Milwaukee and State of Wisconsin, have invented a new, original, and ornamental Design for a Rubber Ball, of which the following is a specification, reference being had to the accompanying drawings, forming part thereof.

The figure is a view in elevation of a rubber ball showing my new design.

I claim:

The ornamental design for a rubber ball, as shown.

ROBERT C. EDDY.
